ELECTRIC DISCHARGE DEVICE

William H. Teare, Ballston Lake, N. Y., assignor
to General Electric Company, a corporation of
New York

Application December 14, 1944, Serial No. 568,085

11 Claims. (Cl. 250—27.5)

1
My invention relates to electric discharge devices and more particularly to improved electrode mounting arrangements for high frequency discharge devices of the magnetron type.

In the design of higher frequency discharge devices, the smaller dimensions encountered render it difficult to provide structures which may readily be assembled and which will insure the required positional accuracy regardless of the skill of the assemblyman. In high frequency electric discharge devices of the magnetron type, it is particularly difficult to provide a structure for mounting the cathode and the space resonant anode structure which maintains axial alignment of the anode and cathode and which does not distort to an undesirable extent the magnetic field in the interelectrode space.

It is an object of my invention to provide a new and improved electric discharge device.

It is another object of my invention to provide a new and improved electrode mounting structure which insures accurate positional relationship between the electrodes.

It is another object of my invention to provide an improved electrode mounting structure which insures adequate cooling of the anode structure.

It is a still further object of my invention to provide an improved electrode mounting for magnetrons which minimizes the distortion of the magnetic field in the interelectrode space.

In the illustrated embodiment of my invention a magnetron of the metal envelope, internal permanent magnet type is provided with novel anode and cathode structures supported from a flange carried by the side wall of the envelope. The anode and cathode structures are both positioned by engagement with accurately finished surfaces on an insulating ring. The accuracy of the final alignment of the electrodes is determined solely by the accuracy of the finished surfaces on the insulating ring and the engaging portions of the anode and cathode structures. Since all of these factors are determined in the production of the parts involved, the positional relationship of the parts is not dependent upon accurate assembly.

For a better understanding of my invention, reference may be had to the following description taken in connection with the accompanying drawing, and its scope will be pointed out in the appended claims. In the drawing, Fig. 1 is an elevational view, in section, of a magnetron embodying my invention; Fig. 2 is a sectional view taken along the line 2—2 of Fig. 1 with the upper magnet removed; Fig. 3 is a perspective view

of the anode and cathode subassemblies, and Fig. 4 is an enlarged detailed view of the cathode support.

2
I have shown my invention embodied in a magnetron device of the sealed metal envelope, internal permanent magnet type. Referring now to the drawing, the envelope comprises a cylindrical portion 1 of steel tubing closed at opposite ends by end plates 2 and 3 which may to advantage be welded to flanges formed on the opposite ends of the tube 1. Internal end plates 4 are welded to the plates 2 and 3 and provided with passages 5 which provide free communication between an exhaust tubulation 6 formed on the end plate 3 and the interior of the envelope 1. The anode and cathode structures of the device are supported in the central portion of the envelope by a flange member 7 which is welded or otherwise secured to the wall of the envelope 10 and is provided with an inwardly extending portion 8 to which the electrode assembly is secured. The cathode assembly includes a cylindrical turned sleeve 9 of nickel or other suitable material on the outer surface of which is applied a coating 20 of thermionically emissive material such as a mixture containing one or more of the alkaline earth oxides. The cathode 9 is provided at one end with a flange 10 which provides an end shield for the interelectrode space. The other end is provided with an accurately finished surface 11 of larger diameter than the active portion of the cathode and which is received in an opening formed in the central portion of a supporting disk or spider 12 for the cathode structure. The disk 12 is preferably a stamping of essentially nonmagnetic sheet metal, such as tantalum, and is provided with three angularly spaced mounting arms 13 for securing the disk to a supporting ring 14 which may to advantage be 25 formed of an insulator such as alumina. Tantalum has substantially the same thermal expansion characteristics as alumina so that a tight fit may be employed without introducing large stresses with changes in temperature. The arms 13 are 30 formed during the stamping operation to provide vertical shoulders 15 which engage the inner surface of the ring 14 to position the disk 12 accurately with respect to the inner surface of the ring 14. A larger flange 16 on the upper 35 end of the cathode 9 is welded to the upper surface of the disk 12 to secure the cathode in position. As a means of heating the cathode element, a small fragmentary heater 17 is provided within the cathode sleeve, with one end 40 secured to the sleeve and the other end extending 45

from the upper end of the sleeve, where it is secured to a strap conductor 18 which is secured in insulated relation with respect to the supporting disk 12 by one of the fastening bolts 19. The bolt 19 passes through a clearance hole in mounting arm 13 and is insulated from the arm by a suitable insulating washer 20. Other fastening bolts 19 secure the remaining arms 13 to the ring 14. As indicated most clearly in Fig. 4, the upper face of the flange 16 in the cathode sleeve is recessed at 21 to allow a small space between the cathode and the heater conductor 18 while maintaining the upper surface of conductor 18 flush with the surface of the disk in the central portion of the cathode assembly.

The anode employed in the illustrated embodiment of my invention is provided with a plurality of space resonant cavities arranged symmetrically about a central opening. Referring to the drawing, a disk or block of copper 22 is provided with a plurality of vanes 23 which extend radially inwardly and define a generally circular opening 24 in which the cathode 9 is received, and which defines with the cathode 9 the inter-electrode space of the device. As is clearly visible in Fig. 3, the vanes define a plurality of wedge-shaped openings in the anode structure, which, as is well understood, function as a plurality of coupled tuned circuits. The anode body or disk 22 is provided with three radially extending arms 24a which are supported on the upper face of the flange 8 and which are secured thereto by mounting bolts 25 which also pass through openings 25a in the ring 14. In order to position accurately the anode structure with respect to the insulating supporting member 14, and as a result to position the anode structure relative to the cathode, I provide a positioning disk 26 which is preferably formed of molybdenum. The centering disk 26 should be preferably nonmagnetic, and of the same or nearly the same thermal expansion as the insulating ring 14. The disk 26 surrounds a central or hub portion 27 of the anode and is held in assembled relation by deforming the upper edge of hub 27 with a punch as indicated at 28.

An output connection for extracting high frequency energy from the device is provided by a wave guide 29 having an opening 30 of rectangular cross section formed therein. As indicated in Fig. 3, the opening in the wave guide is of progressively greater width in the direction away from the anode and, as indicated in Fig. 1, is provided with a quarter wave length filter 32 at its outer end. The wave guide is coupled to one of the wedge-shaped openings in the anode by a slot 33 interconnecting the inner end of the wave guide with the outer wall of one of the resonant slots.

In assembly, the cathode 9 is secured to the supporting disk 12 which is, in turn, secured to the supporting ring 14 by fastening bolts 19. The anode assembly is then positioned in the envelope with the arms 24a resting on the inwardly extending portion 8 of the flange member 7 with the end of the wave guide extending through an opening 34 in the side wall of the envelope and which is enclosed by a thimble 35 welded to the side wall of the envelope. The central portion of the end of the thimble 35 is a glass disk or window 36 located concentrically with respect to the wave guide. The thimble provides a suitable means for coupling the wave guide 29 to an output circuit. With the anode in position, the cathode assembly is placed within the envelope

with the cathode 9 received in the opening 24 of the anode structure and the positioning disk 26 received within and tightly engaging the inner surface of ring 14. The arms 24a of the anode structure are in registry with holes 25a formed in ring 14 between the arms 13 of the cathode supporting disk. The bolts 25 secure both the anode and cathode assemblies securely to the flange. In order to provide clearance for the end of the wave guide, the cathode disk is provided with an opening 37 and the ring 14 is cut away as shown in Figs. 2 and 3.

A magnetic field in the interelectrode space between the anode and cathode is provided by a pair of permanent magnets 38 and 39 which are supported from the opposite ends of the envelope by retaining rings 40 which engage the ends of the magnets and are welded to the end plates 4 of the envelope.

20 The heater and cathode connections are provided by a pair of conductors 41 and 41a which are sealed through a glass member 43 which is, in turn, sealed to a flange 44 on the side wall of the envelope. Conductor 41 is connected by a flexible conductor 42 and terminal 42a to an arm of the cathode disk 12, while the other conductor 41a is connected by a flexible conductor 45 and terminal 45a connected with the heater 17 by the conducting strap 18.

30 With the construction described above, the relative positions of the anode and cathode and the axial alignment of the cathode and the opening in the anode are determined solely by the accuracy of manufacture of the parts from which 35 the assembly is made. The surfaces of the ring 14 are finished ground so that the opposite faces of the ring are parallel and are perpendicular to the inner cylindrical surface of the ring. The positioning disk 26 on the anode assembly and 40 the arms 24a therefore, insure the desired location of the anode and the disk 12 with the positioning shoulder 15 engaging the inner surface of the ring 14 to insure the desired position of the cathode. This structure also provides for a good 45 heat transfer connection between the anode structure and the flange member 7 which is welded to the envelope. Heat from the cathode is conducted by the disk 12 and the lead-in conductors which may be made heavy to increase 50 the heat conducted. The absence of all conductors and supports in the direction parallel to the axis of the cathode cylinder makes it unnecessary to drill openings in the pole pieces, with the result that the magnetic field in the interelectrode 55 space is substantially parallel to the axis of the cathode. The construction is well adapted for either insulated anode or insulated cathode type tubes.

While I have shown and described a particular embodiment of my invention, it will be obvious to those skilled in the art that changes and modifications may be made without departing from my invention in its broader aspects, and I, therefore, aim in the appended claims to cover 65 all such changes and modifications as fall within the true spirit and scope of my invention.

What I claim as new and desire to secure by Letters Patent of the United States, is:

1. A cathode structure including a supporting 70 ring of insulating material, a sheet metal punching having an aperture therein, a plurality of positioning shoulders on said punching in spaced relation about said aperture, and a cathode supported on said punching in said aperture, said punching being supported from said ring with

said shoulders in engagement with a positioning surface of said ring maintaining accurate positional relationship between said ring and said cathode.

2. A cathode structure including a supporting ring of insulating material, a sheet metal punching having an aperture therein and positioning surfaces on said punching in spaced relation about said aperture, and a cathode supported on said punching in said aperture, said punching being supported from said ring with said surfaces in engagement with a positioning surface of said ring maintaining accurate positional relationship between said ring and said cathode.

3. An electric discharge device of the magnetron type comprising a generally cylindrical envelope, an anode structure having a central opening therein and a plurality of openings surrounding said central opening and providing a plurality of coupled cavity resonators, a cathode positioned in said central opening, means supporting and positioning both said anode and said cathode from the side wall of said envelope intermediate the ends thereof, and means for producing a magnetic field in the space between said cathode and the walls defining the central opening of said anode comprising a pair of pole pieces supported from the ends of said envelope and terminating in closely spaced relation with the opposite ends of said cathode, said first mentioned means comprising a ring of insulating material positioned concentrically with the side wall of said envelope and intermediate the ends thereof, a first web member fixed to one end of said ring supporting said anode, a positioning member engaging the inner cylindrical surface of said ring positioning said anode, a second web member fastened to the other end of said ring supporting said cathode, and a plurality of positioning shoulders formed on said second web member engaging the inner cylindrical surface of said ring positioning said second web member.

4. An electric discharge device of the magnetron type comprising a generally cylindrical envelope, an anode structure having a central opening therein and a plurality of openings surrounding said central opening and providing a plurality of coupled cavity resonators, a cathode positioned in said central opening and means supporting and positioning both said anode and said cathode from the side wall of said envelope intermediate the ends thereof, and means for producing a magnetic field in the space between said cathode and the walls defining the central opening of said anode comprising a pair of pole pieces supported from the ends of said envelope and terminating in closely spaced relation with the opposite ends of said cathode, said first mentioned means comprising a ring of insulating material having an accurately finished inner cylindrical surface positioned concentrically with the side wall of said envelope and intermediate the ends thereof, a first web member fastened to one end of said ring supporting said anode, a positioning member engaging the inner cylindrical surface of said ring positioning said anode, a second web member fastened to the other end of said ring supporting said cathode, and a plurality of positioning shoulders formed on said second web member and engaging the inner cylindrical surface of said ring positioning said second web member.

5. An electric discharge device of the magnetron type comprising a generally cylindrical envelope, an anode structure having a central open-

ing therein and a plurality of openings surrounding said central opening and providing a plurality of coupled cavity resonators, a cathode positioned in said central opening and means supporting and positioning both said anode and said cathode from the side wall of said envelope intermediate the ends thereof, and means adjacent said cathode for producing a magnetic field in the space between said cathode and the walls defining the central opening of said anode in a direction substantially parallel to the axis of said cathode terminating in closely spaced relation with the opposite ends of said cathode, said first mentioned means comprising a ring of insulating material positioned concentrically with the side wall of said envelope and intermediate the ends thereof, a first web member fastened to one end of said ring supporting said anode, a positioning member engaging the inner cylindrical surface of said ring positioning said anode, a second web member fastened to the other end of said ring supporting said cathode, and a plurality of positioning shoulders formed on said second web member engaging the inner cylindrical surface of said ring positioning said second web member.

6. An electric discharge device of the magnetron type comprising an envelope, an anode including a plurality of cavity resonators surrounding a central opening, a cylindrical cathode, means supporting said anode and said cathode in insulated relation from a side wall of said envelope with said cathode positioned in said central opening, and means including pole pieces extending in the direction of the axis of the cylindrical cathode for producing a magnetic field between said anode and said cathode, said first mentioned means comprising a ring of insulating material positioned concentrically with the side wall of said envelope and intermediate the ends thereof, a first web member fastened to one end of said ring supporting said anode, a positioning member engaging the inner cylindrical surface of said ring positioning said anode, a second web member fastened to the other end of said ring supporting said cathode, and a plurality of positioning shoulders formed on said second web member engaging the inner cylindrical surface of said ring positioning said second web member.

7. An electric discharge device comprising an anode having a circular opening therein, a cathode centered within said circular opening within said anode, supporting means having fastening surfaces and positioning surfaces positioned laterally of said anode and said cathode in spaced relation thereto, means engaging one of said fastening surfaces and said anode supporting said anode in spaced relation to said supporting means, means engaging one of said positioning surfaces and said anode positioning said anode within said supporting means, means engaging one of said fastening surfaces and said cathode supporting said cathode in spaced relation to said supporting means, and means engaging one of said positioning surfaces positioning said cathode centrally within said circular opening in said anode.

8. An electric discharge device comprising a generally annular anode having a circular opening therein, a cathode centered within said circular opening within said anode, supporting means having fastening surfaces and positioning surfaces surrounding said anode and said cathode in spaced relation thereto and positioned generally in the plane of said anode, means engaging one of said fastening surfaces and said anode supporting said anode in spaced relation to said sup-

porting means, means engaging one of said positioning surfaces and said anode positioning said anode within said supporting means, means engaging one of said fastening surfaces and said cathode supporting said cathode in spaced relation to said supporting means, and means engaging one of said positioning surfaces positioning said cathode centrally within said circular opening in said anode.

9. An electron discharge device comprising, an anode of generally annular configuration, a cathode centered within said anode, an annular support of insulating material positioned concentrically about said anode and said cathode in spaced relation thereto, means engaging said support and said anode positioning said anode centrally of said support and in spaced relation thereto, and means engaging said support and said cathode positioning said cathode centrally within said anode, said first mentioned means comprising a web member fastened to one end of said annular support and a positioning member engaging the inner surface of said annular support, said second mentioned means comprising a web member fastened to the other end of said annular support and a plurality of positioning shoulders formed thereon and engaging the inner surface of said annular support.

10. An electron discharge device comprising, an envelope, an anode, a cathode in spaced relation to said anode, an annular support of insulating material supported from the side wall of said envelope intermediate the ends thereof, means engaging said support and said anode positioning said anode centrally of said support and in spaced relation thereto, and means engaging said support and said cathode positioning said cathode in spaced relation to said anode, said first mentioned means comprising a web member fastened to one end of said annular support and a positioning member engaging the inner surface of said annular support, said second mentioned means comprising a web member fastened to the other end of said annular support and a plurality of positioning shoulders formed thereon and engaging the inner surface of said annular support.

11. An electron discharge device comprising, an anode of generally annular configuration, a cathode centered within said anode, an annular support of insulating material positioned concentrically about said anode and cathode in spaced relation thereto, said support having an inner cylindrical surface and end surfaces perpendicular thereto, means engaging said support and said anode positioning said anode centrally of said support and in spaced relation thereto, means engaging said support and said cathode positioning said cathode centrally within said anode, said first mentioned means comprising a web member fastened to one of the end surfaces of said annular support and a positioning member engaging the inner cylindrical surface thereof, said second mentioned means comprising a web member fastened to the other end of said annular support and a plurality of positioning shoulders formed thereon and engaging the inner cylindrical surface of said annular support.
